(57) **CLAIM**

I claim the ornamental design for socket containing device, as shown and described.

DESCRIPTION

FIG. 1 is a front perspective view of a socket containing device;

FIG. 2 is a rear perspective view thereof;

FIG. 3 is a top plan view thereof; and,

FIG. 4 is a bottom plan view thereof.

The portions of the socket containing device shown in broken lines form no part of the claimed design.
